AUTOGRAPHIC REGISTER

Louis E. Zurbuchen, Zurich, Switzerland, assignor
to The National Cash Register Company, Dayton, Ohio, a corporation of Maryland

Application March 10, 1948, Serial No. 13,985

3 Claims. (Cl. 235—2)

1.

This invention relates to improvements in autographic registers equipped with a totalizer and a cash drawer.

The principal object of the invention is to provide an improved autographic register in which data to be printed on an autographic strip, and entered into a totalizer, is set up on a series of slides, which slides are unitary members carrying type characters and totalizer actuators.

Another object of the invention is to provide a novel printing mechanism which is released to make impressions on an autographic strip before the machine starts to operate.

Another specific object of the invention is to provide a release key for an autographic register, which when depressed releases the printing mechanism to take an impression on record material, and which subsequently releases a cash drawer, and through the latter releases the register for operation.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

Of said drawings:

Fig. 1 is a perspective view of the autographic register.

Fig. 2 is a cross-sectional view taken just inside the right side frame and looking toward the left when viewing the register from the front.

Fig. 3 is a time chart showing the time of operation of the various mechanisms of the register.

GENERAL DESCRIPTION

The invention embodies an autographic register with a totalizer and a cash drawer, of simple and inexpensive construction. Manipulative devices are provided for setting up data to be printed on an autographic strip and to enter amounts into a totalizer. A novel and simple construction of each manipulative device consists of a unitary member having a lever protruding through the cabinet, by means of which the member is manually set; type characters thereon; and an actuator rack for entering amounts into the totalizer element. After said unitary member has been manually set, a spring-actuated printing hammer is released by the initial depression of a release key on a keyboard, and complete depression of the release key unlatches the cash drawer to the action of a spring.

40

45

50

55

It is a feature of construction of the machine to print the data before the cash drawer is unlatched. Release of the cash drawer releases the operating mechanism of the machine to restore any tens transfer which may have been tripped during the previous operation; to cock the autographic strip feed mechanism; to cock the ribbon feed mechanism; and to restore the release key to its normal position. Manual closing of the cash drawer restores the operating mechanism to normal position, during which time the unitary members are tilted to engage the actuator racks thereon with the totalizer elements, whereupon the unitary members are restored to normal position, and, since at this time these unitary members are in engagement with the totalizer elements, the data represented by the setting thereof is added into the totalizer. After the data has been entered into the totalizer, the unitary members are tilted back to disengage them from the totalizer elements. After the unitary members are disengaged from the totalizer elements, the tens transfers are entered wherever required. During the manual closing operation of the cash drawer, the operating mechanism also linespaces the autographic strip and feeds the ribbon. A spring to open the cash drawer and initially actuate the operating mechanism is stretched by the cash drawer when the cash drawer is manually closed whereupon the cash drawer is latched, ready to be released for the next operation.

It should be noted that the operating mechanism has no heavy load during the first half of the machine operation, and since during this operation only preparatory functions are performed, such as restoring the tens transfer mechanism and cocking the autographic strip and ribbon feed mechanisms, thereafter, when the cash drawer is closed manually, the positive operations consisting of engaging the actuator racks with the totalizer, entering data into the totalizer, entering the tens transfers, feeding the autographic strip, and feeding the ribbon are performed.

An opening is also provided for receiving an insertable slip for receiving printed entries thereon.

DETAILED DESCRIPTION

The machine is provided with a base 10 (Figs. 1 and 2), in which a cash drawer 11 is slidably mounted. Supported on the base 10 is a cabinet 12 for housing the mechanism of the machine. A series of slots 13 are provided in the top of the

cabinet 12, through which finger pieces 14 of a group of unitary members 15 protrude. Indexes to guide the operator in properly setting the unitary members 15 are provided adjacent the slots 13. As shown in Fig. 1, these indexes are illustrated with characters to represent "0" to "9," which characters are used for setting up amounts. Any other character may be provided adjacent the slots 13 if any other data is to be printed on the audit strip. A second series of slots 16 (Fig. 1) are provided for guiding the unitary members 15 in their movements.

The unitary members 15 are mounted at their forward ends on a rod 17 carried by the side frames of the machine. A second rod 18, carried by a pair of pitmans 19, only one being shown herein, projects through slots 20 of the unitary members 15 to support them at their rear ends. The rod 18 is raised and lowered during each machine operation in a manner hereinafter described to engage an actuator rack 21, formed on the rear of each unitary member 15, with a pinion on an associated totalizer element 22, one pinion being provided for each unitary member 15.

The unitary member 15 is also provided with type characters 23, which characters are selectively positioned into the path of a printing hammer 24 when manually adjusted.

An aliner 9 is provided to properly align and hold the unitary members in the adjusted positions. A spring 8 is provided to maintain the aliner 9 in effective position.

It is an important feature of the present invention to provide the novel unitary member 15 with the finger piece 14, the type character 23, and the actuator rack 21. The novel construction of utilizing a unitary member to perform all the functions of type setting and amount entering eliminates the necessity of expensive differential mechanisms, as are usually provided in machines of this class.

Printing hammer mechanism

The printing hammer 24 is pivotally mounted on a stud 25 and is normally held in a cocked position by a trip pawl 26 carried by a stud 27 on a link 98, hereinafter described. The printing hammer is provided with a shoulder 28 engaged by a forwardly-extending arm 29 of the trip pawl 26. A spring 30, one end of which is secured to the printing hammer and the other end on a stud in the machine frame, is normally stretched, ready to operate the printing hammer.

It is a feature of the present machine to trip the printing hammer 24 to make a printed record on the autographic strip before the cash drawer 11 is released to release the main operating mechanism of the machine.

The release of the hammer is accomplished during the initial movement of a release key 31 projecting through an opening in the cabinet 12. The release key 31 is provided with a slot 32, through which projects a stud 33 carried by a bell crank 34 pivoted on a stud 35 carried by the framework of the machine. The lower end of the bell crank 34 has pivoted thereon a plunger 36, which is slidably mounted in a cross bracket 37. The free end of the plunger 36 lies in the plane of an upstanding finger 38 of the trip pawl 26. A spring 39, coiled around the plunger 36, normally maintains the bell crank 34 and the release key 31 in their undepressed position. Depression of the release key acting through the slot 32 and the stud 33 rocks a bell crank 34

clockwise, thus moving the plunger 36 to the left, as viewed in Fig. 2, to engage and rock the trip pawl 26 counter-clockwise against the action of a spring 40. The spring 40 is connected to the trip pawl 26 at one end, and the other end is connected to a feed pawl 41 for the autographic strip, hereinafter described. Counter-clockwise rotation of the trip pawl 26 withdraws the forward end of the finger 38 from engagement with the shoulder 28 on the printing hammer and permits the spring 30 to rapidly rotate the printing hammer 24 in a counter-clockwise direction to make an impression on the autographic strip 42. After the trip pawl 26 has been rocked to release the printing hammer, the release key, upon further depression, withdraws a latch 46, pivotally mounted on a rod 45 carried by the framework of the machine, to release the cash drawer 11. The drawer latch 46 engages the inner rear wall of the cash drawer to normally maintain the cash drawer in its latched position. The forward end of the drawer latch 46 is provided with a stud 43, which projects into a slot 44 in the lower end of the release key 31. The slot 44 is of sufficient length to permit the trip pawl 26 to release the printing hammer for operation before engagement of the release key with the stud 43, which, therefore occurs after the impression has been made on the autographic strip, thus permitting the cash drawer to be opened by the main operating mechanism in a manner to be presently described.

Main operating member

The mechanism of the machine is operated by a main operating member 50 pivotally mounted on a shaft 51 supported by the side frames of the machine. A spring 52, connected to a stud 53 on the main operating member 50 and on a lug 54 on the base of the machine, normally tends to rock the main operating member 50 in a clockwise direction. Clockwise rocking movement of the main operating member is normally prevented by a stud 55 carried by the cash drawer. When the release key 31, through the slot 44 and the stud 43, rocks the drawer latch 46 counter-clockwise to withdraw its free end from engagement with the inner back wall of the cash drawer, the spring 52 is released to rock the main operating member 50 clockwise and through the stud 55 moves the cash drawer 11 into its open position. A rod 56, carried by the side frames of the machine, limits the clockwise rotation of the main operating member 50, as shown by the chain lines in Fig. 2.

In order to add stability to the operation of the main operating member 50, a second main operating member can be provided at the left side of the machine, and in this event the two main operating members 50 are pinned to the shaft 51, so that the two members 50 and the shaft 51 would act as a unitary frame. In this construction a stud 55 is also provided on the left side of the cash drawer.

Totalizer engaging mechanism

The main operating member 50 is provided with a cam slot 60 and a by-pass pawl 61, which coacts with the cam slot 60 to properly operate the pitman 19. The pitman 19 is provided with a stud 62, which projects into the cam slot 60. As shown in the time chart (Fig. 3), the actuator rack 21 is engaged with the totalizer element 22 during the return movement of the cash drawer 11. When the cash drawer 11 is returned into

the base of the machine manually, the stud 55, by engagement with the main operating member 50, restores the main operating member to its normal position, thus storing up energy in the spring 52 for the next operation of the machine. It is during this manual restoring movement by the operator that the rack 21 is moved into engagement with the totalizer element 22. For this reason, it is necessary that the cam slot 60 does not become effective during the original clockwise movement of the main operating member. This result is obtained by providing the by-pass pawl 61, pivoted on a stud 63 carried by the main operating member. The by-pass pawl 61 is provided with a flange 64 having a cam edge 65, which comes into engagement with the stud 62, and the by-pass pawl is thereby rocked counter-clockwise against the action of a spring 66. During the return movement of the main operating member, the stud 62 is engaged by a cam edge 67 of the by-pass pawl 61 to cam the stud 62 upwardly. Upward movement of the stud 62 raises the pitman 19 and, through the rod 18, raises the unitary members 15 upwardly to engage the totalizer actuator 21 with the pinions on the totalizer element 22. After the actuators 21 have been engaged with the totalizer element 22, the unitary members 15 are automatically restored to their normal positions by mechanism hereinafter described, to enter the amounts represented by the setting of the unitary member into the totalizer element. After an amount has been entered into the totalizer, the cam 60, engaging the stud 62, cams the pitmans 19 downwardly to again disengage the rack 21 from the totalizer element. The pitman 19 is guided in its up-and-down movements by the shaft 51 at its lower end and by a stud 68, on the frame of the machine, at its upper end.

Totalizer rack restoring mechanism

Each of the unitary members 15 is provided with a downwardly-extending finger 70, lying in the plane of a rod 71, carried by a pair of floating bell cranks 72 (only one of which is shown) pivotally mounted on a shaft 73. The bell crank 72 is provided with a stud 74, on which normally rests an operating pawl 75 pivoted on a stud 76 carried by the main operating member 50. During the initial movement of the main operating member 50—that is, when the cash drawer is released by raising the drawer latch 46—the pawl 75 is rocked rearwardly until a shoulder 77 thereon drops over the stud 74. When the cash drawer is returned to its closed position, the main operating member 50 restores the pawl 75 to the normal position, shown in Fig. 2. As the pawl 75 is restored to its normal position, it, being in engagement with the stud 74, rocks the bell crank 72 clockwise, which, through the rod 71 engaging the fingers 70, restores the unitary members 15, and therefore the totalizer actuator racks, to their normal positions, thus entering the amount standing on the rack into the totalizer elements. Near the end of the restoring movement of the pawl 75, a cam surface 78, formed on the under side of the pawl 75, coming into engagement with the shaft 51, raises the pawl 75 to disengage the shoulder 77 from the stud 74, thus restoring the pawl 75 to the position shown in Fig. 2.

The bell cranks 72 are limited in their counter-clockwise movement by a rod 79 carried by the side frames of the machine. The position which the bell crank 72 assumes after the machine operation is not important, since, when the unitary members 15 are set up for the next opera-

tion, the rod 71 will be moved an extent necessary by the movement of the unitary member having the greatest extent of movement. Thereafter, when the machine is operated, the pawl 75 will come into contact with the stud 74 at a time depending upon the position of the bell crank 72. As illustrated in Fig. 2, the bell crank 72 is in its farthest counter-clockwise position. Except for the force of gravity, the bell crank 72 and the rod 71 would normally come to rest in engagement with the fingers 70 instead of in engagement with the stop stud 79.

In order to lighten the force required to restore the unitary members 15, a link 84, pivoted on pitman 19, is provided to raise the aliner 9. The link is slotted at its upper end to engage a stud 85, carried by the aliner 9. When the pitman is raised upon operation of the main operating member 50, the link 84 is raised to lift the aliner out of the aliner notch in the unitary member 15.

Tens transfer mechanism

Any form of tens transfer mechanism may be used in the totalizer, and, since it is not a feature of this invention, such a tens transfer mechanism has not been shown in detail. However, the totalizer element 22 is illustrated with a tens transfer ratchet wheel 80, which may be actuated by pawls in the manner shown in the United States Patent to Ernst Breitling, No. 2,209,763, issued on July 30, 1940. A link 81 is illustrated, pivoted on the stud 63 for actuating cams for operating the tens transfer pawls. The time chart (Fig. 3) shows the time of entering the tens transfers when this form of tens transfer mechanism is used.

Autographic strip

The autographic paper strip 42 is fed from a supply roll 90, resting in a trough 91 carried by the framework of the machine over a guide rod 92 past a glass window 93 over a guide rod 94 and onto a receiving roller 95. The receiving roller 95 is rotatably mounted on a shaft 96 and is provided with a feed ratchet 97, which is engaged by the before-mentioned feed pawl 41. The feed pawl 41, together with the printing hammer trip pawl 26, is pivotally supported on a link 98, the right-hand end of which is pivoted on a stud 99 carried by the main operating member 50. The link 98 is supported to slide in a slot cut in the cross frame 37. When the main operating member 50 is rocked clockwise by the spring 52, the link 98 is withdrawn to the right (Fig. 2) to move the feed pawl 41 far enough to drop behind the next tooth in the ratchet 97. When the cash drawer is restored to its closed position and the main operating member 50 is rocked counter-clockwise, the link 98 is moved toward the left (Fig. 2), whereupon the feed pawl 41 rotates the ratchet wheel 97 and the receiving roll 95 to line-space the printed item on the autographic strip 42. At this time, the trip pawl 26 comes into engagement with the shoulder 28 on the printing hammer and cocks the printing hammer, ready for the next machine operation.

A non-retrograde movement pawl 100 is pivotally mounted on a stud 101 carried by the machine framework and is held in engagement with the ratchet wheel by a spring 102.

The window 93 is provided with an opening 103 (Fig. 1), through which written entries can be made on the autographic strip 42 adjacent any printed entry. A writing table 104 (Fig. 2) is supported beneath the opening 103 and is pro-

vided to form a table in making the written entries. The table 104 is spring-cushioned by a spring 105.

Insertable slips

The machine is also arranged to permit printing on insertable slips if desired. The insertable slip 105, either in duplicate, or a single slip, may be inserted on the glass window 93 and through a slot in the cabinet 12, as shown in Fig. 2. A ribbon 110 is provided for taking the impressions either on the insertable slip or on the autographic strip 42. If an insertable slip is used, carbon paper must be used for making the impression on the second strip of the duplicate insertable slip and on the autographic strip 42.

Any suitable ribbon feed mechanism may be provided, which will be operated according to the time shown on the time chart (Fig. 3).

OPERATION

In the use of the machine, the operator first grasps the finger piece 14 on the unitary member 15 and sets up the amount to be entered with the aid of the index on the cabinet adjacent the slots in which the finger piece 14 moves. The timing of the setting of the unitary member 15 is shown in line 8 of the time chart (Fig. 3). After the unitary members 15 have been properly adjusted, the release key 31 is depressed (line 2, Fig. 3). The initial movement of the release key 31, through the slot 32 and the pin 33, trips the release pawl 26 to release the printing hammer 24 to the action of the spring 30 to make the entry on the autographic strip 42 and on the insertable sales slip if an insertable sales slip is positioned in the machine. The timing of the operation of the printing hammer 24 is shown in line 3 of the time chart (Fig. 3). Further depression of the release key 31, acting through the slot 44 and the stud 43, releases the cash drawer to the action of the spring 52 and the main operating member 50 (line 1, Fig. 3). As shown in the time chart (line 1, Fig. 3), during the time the cash drawer is moved to its open position, the release key is restored to its normal position (line 2, Fig. 3), the tens transfer mechanism is restored to its home position (line 5, Fig. 3), the autographic feed strip pawl 41 is moved rearwardly ready to start a feeding operation (line 6, Fig. 3), and the ink ribbon feed mechanism is cocked, ready for operation (line 7, Fig. 3). Closing of the cash drawer (line 1, Fig. 3) rocks the main operating member 50 counterclockwise. At the beginning of this restoring movement of the cash drawer, the pitmans 19 are raised by the main operating member to engage the actuator 21 with the totalizer elements 22 (line 4, Fig. 3). After the actuator 21 has been engaged with the totalizer elements, the racks are returned to normal position (line 8, Fig. 3) by operation of the pawl 75 and the bell cranks 72, which, through the stud 71 engaging the fingers 70 on the unitary member 15, restores the racks to their normal positions (line 8, Fig. 3), thus entering the amounts into the totalizer elements 22. After the amounts have been added into the totalizer elements 22, the pitmans 19 are again lowered (line 4, Fig. 3) to disengage the actuator 21 from the totalizer elements. After this operation, the tens transfer pawls which have been tripped are operated by the link 81 to enter the tens transfers which are required (line 5, Fig. 3). During the restoring movement of the cash drawer, the autographic strip is fed (line 6, Fig. 3) and the ribbon feed mechanism

is also operated (line 7, Fig. 3). During this restoring movement of the cash drawer, the printing hammer 24 is cocked by the release pawl 26 (line 3, Fig. 3), ready to release the printing hammer upon the next operation of the release key 31.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described, a slide, type characters formed on the slide, a totalizer actuator formed on the slide, a finger piece formed on the slide by means of which the slide can be set from a normal position into any one of a plurality of settable positions, in combination with a totalizer element mounted on a fixed support, a slot in the slide, a link having a projection thereon projecting into the slide whereby the slide can be shifted to move the totalizer actuator into engagement with the totalizer element, an operating member, a cam formed in the operating member coacting with the link to shift the link after the slide has been set into one of said plurality of settable positions to shift the slide and engage the totalizer actuator with the totalizer element, a projection on the slide, a floating member, and a pawl connected to the operating member for actuation thereby, said pawl movable into engagement with the floating member during an operation of the operating member to rock the floating member whereby the floating member engages the projection on the slide and restores the slide to normal position to enter an amount commensurate with the set position of the slide into the totalizer element.

2. In a machine of the class described, a slide, type characters formed on the slide, a totalizer actuator formed on the slide, a finger piece formed on the slide by means of which the slide can be set from a normal position into any one of a plurality of settable positions, in combination with a totalizer element mounted on a fixed support, a slot in the slide, a link having a projection thereon projecting into the slide whereby the slide can be shifted to move the totalizer actuator into engagement with the totalizer element, a spring tensioned operating member, a latch to normally maintain the spring tensioned operating member in home position; a cam formed in the operating member coacting with the link to shift the link after the slide has been set into one of said plurality of settable positions to shift the slide and engage the totalizer actuator with the totalizer element, a projection on the slide, a floating member, a pawl connected to the operating member for actuation thereby, said pawl movable into engagement with the floating member during an operation of the operating member to rock the floating member whereby the floating member engages the projection on the slide and restores the slide to normal position to enter an amount commensurate with the set position of the slide into the totalizer element, and a manipulative device to operate the latch to release the spring tensioned operating member for operation.

3. In a machine of the class described, a slide, type characters formed on the slide, a totalizer actuator, formed on the slide, a finger piece

formed on the slide by means of which the slide can be set from a normal position into any one of a plurality of settable positions, in combination with a totalizer element mounted on a fixed support, a slot in the slide, a link having a projection thereon projecting into the slide whereby the slide can be shifted to move the totalizer actuator into engagement with the totalizer element, a spring tensioned operating member, a latch to normally maintain the spring tensioned operating member in home position, a normally cocked spring-tensioned printing hammer to take impressions from the type characters, a pawl to normally maintain the printing hammer cocked, and a manipulative device operable to first actuate the pawl to release the printing hammer and thereafter operate the latch to release the spring tensioned operating member, whereby a printed record is made before the machine starts to operate.
